OSCAR C. DAVIS, OF BROCKTON, MASSACHUSETTS.

SHOE AND FULL-LENGTH OUTER-SOLE THEREFOR.

1,191,498.

Specification of Letters Patent. Patented July 18, 1916.

Application filed March 6, 1916. Serial No. 82,308.

To all whom it may concern:

Be it known that I, OSCAR C. DAVIS, a citizen of the United States, residing at Brockton, in the county of Plymouth and State of Massachusetts, have invented new and useful Improvements in Shoes and Full-Length Outer-Soles Therefor, of which the following is a specification.

This invention relates to a shoe having a full length outer sole which includes a heel portion forming a seat for the usual heel of leather or other suitable material, seated on and projecting below the heel end of the outer sole.

15 The invention has for its object, first, to provide, as an article of manufacture, a full length outer sole composed of a fore portion and a shank portion formed in one piece from relatively inelastic material such as leather, and a heel portion of elastic material attached to the shank portion, the whole forming a combined outer sole and cushioning heel seat which is attachable as a single piece or part to the inner sole and 25 upper of a shoe, the elastic heel portion constituting a heel seat which is not only utilized as such but also as a cushion for a practically rigid heel.

The invention also consists in a shoe including a full length outer sole characterized as above stated.

Of the accompanying drawings forming a part of this specification: Figure 1 represents a top view of an inner sole embodying my invention; Fig. 2 represents a bottom view of the same; Fig. 3 represents a section on line 3—3 of Fig. 2; Fig. 4 represents, partly in elevation and partly in section, a shoe the bottom of which includes the full 40 length composite outer sole shown by the preceding figures.

The same reference characters indicate the same or similar parts in all the views.

In carrying out my invention I provide a full length outer sole composed of a fore portion 12, a shank portion 13 formed in one piece therewith, said portions being of suitable relatively inelastic wear-resisting material such as sole leather, and a heel portion 14 of elastic material such as rubber or a composition containing rubber.

The elastic heel portion 14 is united to the shank portion 13 by a transverse joint preferably formed by scarfing the rear end of the shank portion to form a beveled face 13^a, and by scarfing the forward end of the heel

portion to form a beveled face 14^a, said faces being abutted together and united by a film of cement.

The sole thus constructed is adapted to be incorporated in a shoe in any suitable way, and is handled as a single piece or part.

A saving in the cost of manufacture is effected, especially when the fore and shank portions are made of sole leather, by reason of the fact that the elastic heel portion, imparting a full length to the outer sole, costs less than the corresponding area of sole leather formed integral with the shank portion. The heel portion 14 also constitutes an elastic seat and cushion for the usual heel 15, said heel being secured to the body of the shoe by suitable means, such as nails 16, passing through the heel portion 14 and engaged with the heel portion of the usual inner sole 17, as shown by Fig. 4.

The length of the heel 15 is preferably such that its forward portion covers the joint formed by the cemented faces 13^a and 14^a.

It will now be seen that the composite full length outer sole above described is adapted to be handled, and incorporated in the shoe, as a single part, involves no departure from the usual methods of bottoming the shoe, decreases the expense of the outer sole as a whole, and provides a cushioning heel seat for the usual heel of the shoe.

I use the term relatively inelastic to characterize a material such as sole leather, which is much less elastic than the rubber of which the heel portion 14 is composed.

Having described my invention, I claim:

1. As an article of manufacture, a full length outer sole composed of a fore portion and a shank portion formed in one piece from relatively inelastic material, and a heel portion of elastic material formed separately from and attached to the shank portion and forming a cushioning heel seat.

2. As an article of manufacture, a full length outer sole composed of a fore portion and a shank portion formed in one piece from relatively inelastic material, and a heel portion of elastic material attached to the shank portion and forming a cushioning heel seat, the said shank and heel portions being provided with scarf'd faces united by cement.

3. A shoe comprising an upper, an inner sole, a full length outer sole composed of a fore portion, a shank portion formed in one

piece with the fore portion from relatively inelastic material, and a heel portion of elastic material attached to the shank portion, and a heel seated on said elastic heel portion and attached thereto and to the inner sole.

4. A shoe comprising an upper, an inner sole, a full length outer sole composed of a fore portion, a shank portion formed in one piece with the fore portion from relatively inelastic material, and a heel portion of

elastic material attached to the shank portion, and a heel seated on said elastic heel portion and attached thereto and to the inner sole, the said shank and elastic heel portions being united by a transverse joint and the heel being formed to cover said joint. 15

In testimony whereof I have affixed my signature.

OSCAR C. DAVIS.
